J. B. PERKINS

TOOL

Filed June 28, 1921

UNITED STATES PATENT OFFICE.

JAMES B. PERKINS, OF OAKLAND, CALIFORNIA.

TOOL.

Application filed June 28, 1921. Serial No. 481,130.

To all whom it may concern:

Be it known that I, JAMES B. PERKINS, a citizen of the United States, residing at Oakland, in the county of Alameda and 5 State of California, have invented new and useful Improvements in Tools, of which the following is a specification.

My present invention has reference to a combination tool which is especially designed for the use and convenience of forest 10 rangers whose duties are to protect the forest from the ravages of fires.

Fires in forests originate from many different causes; often electric storms cause a 15 fire to break out high up on a mountain side, and in order for the forest rangers to reach it, they are compelled to pass through dense thickets of underbrush, over fallen timber and rough ground, and as the carrying of 20 the old fashioned shovel, grub hoe and pick with their long and heavy handles greatly retard the progress of the rangers, they not infrequently reach the fire with no tools to combat the flames.

It is therefore to be considered the primary object of the present invention to provide an axe designed to be carried in the belt of the ranger and having means whereby implements, such as a shovel, pick and 30 grub hoe, necessary in fighting forest fires, can be attached to the axe and also conveniently carried in the belt of the ranger.

The drawings illustrate a satisfactory embodiment of the invention reduced to practice, and in which:—

Figure 1 is an elevation showing an axe having attached thereto a grub hoe.

Figure 2 is a sectional view through the axe head, in a line with the shank of the 40 grub hoe.

Figures 3 and 4 are side elevations of the shovel and pick respectively.

Figure 5 is a view substantially similar to Figure 2, with the tool removed from 45 the opening in the axe head.

Figure 6 is a view of a wrench suitable for use with the tool.

In the successful fighting of forest fires, a shovel is needed for carrying soil or gravel 50 for smothering the fire. A grub hoe is useful for trenching and digging around the fire to prevent it from spreading or getting away, while a pick is useful for removing fences, posts, rails, ties, or piles of lumber

or building that are on fire and are impossible to handle with the naked hands, while the axe is required for a multiplicity of purposes. Therefore, this combination of tools is indispensable in the successful fighting of forest fires. 55

Referring now to the drawings in detail, the numeral 1 designates an axe such as is commonly used by hunters and forest rangers. The helve or handle 2 of the axe is of a comparatively short length so that the 60 same can be conveniently carried in the belt of the ranger. Also the belt is provided with loops or compartments for receiving therein a grub hoe 3, a pick 4 and a shovel 5. The shanks of all of these instruments 65 are similarly constructed, and therefore, reference to one is to be considered as equally applicable to the remainder.

The axe head 1, inward of the blunt end thereof is provided with a transverse opening therethrough. The outer portion of this opening is squared, as at 6, the inner portion being rounded, as at 7. The shank 8 of each of the implements has its inner portion squared, as at 9 and its outer portion rounded and threaded, as at 10. The shanks 8 are of a size to be snugly received in the opening in the axe head, the squared portion 9 of the said shanks being in contacting engagement with the squared walls 6 75 of the opening, the rounded and threaded portions 10 of the shanks passing through the rounded portions 7 of the opening, and the said threaded portions are engaged by a nut 11 screwed thereon by a suitable 80 wrench 12 which is also carried in a suitable compartment in the belt of the ranger. 85

Having described the invention, I claim:

An axe having its head provided with a perforation extending in a direction parallel 90 to the axis of the handle, the walls of said perforation being tapered inwardly from one end and merging into a cylindrical bore, said perforation being adapted to receive tools including a grub hoe, a pick and a 100 shovel, each having a threaded shank complementary to the perforation and adapted to be secured therein by a nut engaging the threaded end of said shank.

In testimony whereof I affix my signature. 105

JAMES B. PERKINS.
